Primary Examiner — April Rivas*Assistant Examiner* — Dustin Andrew Griffith(74) Attorney, Agent, or Firm — Ricky Lam(57) CLAIM

The ornamental design for a sports bag, as shown and described.

DESCRIPTION

FIG. 1 is a front perspective view of a sports bag, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view.

The broken lines in the drawings illustrate the portions of the sports bag, which form no part of the claimed design.
